UNITED STATES PATENT OFFICE

RALPH H. CHILTON, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed November 18, 1926. Serial No. 149,107.

This invention relates to refrigerating apparatus and particularly to apparatus of the household type including a refrigerator cabinet having communicating food and cooling chambers, the latter chamber containing a cooling unit or evaporator connected with a refrigerating machine.

One object of the present invention is to quickly cool a liquid, such as water, and to provide for the circulation of the liquid in order to prevent freezing.

More particularly the invention relates to certain improvements in the type of liquid cooling apparatus described and claimed in the copending application of Lloyd M. Keighley, Serial No. 149,103, filed November 18, 1926. In said application, liquid may be stored in two containers, one in close proximity to the cooling unit and the other subjected to a warmer temperature outside the cabinet. These containers are connected so that circulation of water by convection will be established. It is apparent that such apparatus would not be the most economical since heat transfer may readily take place through the water circulation system between the outside of the cabinet and the cooling unit. In the present invention, the container, which is subjected to warmer temperature conditions, is placed in close proximity to the warmer air circulating in the food chamber and is so constructed and arranged as not to encroach upon the space required for the food chamber and the space required for the circulation of air around the cooling unit.

Further objects and advantages of the present invention will be apparent from the following description, reference being had to the accompanying drawings, wherein a preferred embodiment of one form of the present invention is clearly shown.

In the drawings:

Fig. 1 is a diagram showing the application of the present invention to a refrigerator cabinet of the household type;

Fig. 2 is a view on a larger scale than Fig. 1 and shows a front elevation of a cooling unit and water cooling apparatus, the walls of the refrigerator cabinet being shown in vertical section; and

Figs. 3 and 4 are sectional views taken respectively on the lines 3-3 and 4-4 of Fig. 2.

Referring to the drawings, 20 designates a refrigerator cabinet having a food chamber 21 and a cooling chamber 22. The chamber 22 contains a cooling unit which comprises an elongated header 23 and a plurality of pipe loops 24 of metal of good thermal conductivity connected therewith. These loops 24 provide vertical ducts 25 which are arranged in spaced horizontal rows. The inside rows cooperate with a header to provide a quick freezing space 26 which is adapted to receive one or more metal sleeves 27 which are attached to and thermally connected with the inside rows of ducts 25. Each tray 27 is adapted to receive a metal tray 28 for containing matter to be frozen. The header 23 is supported from the top wall of the cabinet by brackets 29 and 30. Liquefied refrigerant is conducted from a refrigerating machine to the header 30 through a pipe 31 and a fitting 32, and gasified refrigerant is returned to the machine through a fitting 33 and a pipe 34.

The chamber 22 is separated from the chamber 21 by a horizontal partition 40 provided with a flue 41 for admitting chilled air from the chamber 22 to the food chamber 21. The vertical wall for separating chambers 21 and 22 is provided in part by a relatively thin, vertically elongated tank or container 42 having its bottom wall adjacent the partition 40 and its top wall spaced substantially below the top wall of the cabinet to provide an opening for admitting warm air passing from the chamber 21 over the container 42 and into the chamber 22 each indicated by arrow 43 in Fig. 1. The horizontal depth of the container 42 is substantially equal to the distance between the front wall 44 and the back wall 45 of the cabinet. The container 42 is supported by means of plates 46 which are spaced apart as shown in Fig. 4 to provide a passage 47 between the upper part of the food chamber and the upper part of the cooling chamber. Each plate 46 is provided with a flange 48 permanently secured to the top wall of the container 42 and

with a flange 49 detachably secured in any suitable manner to the top line wall of the cabinet. The container 42 is also supported to the back line wall of the cabinet by one or more brackets 50.
 5 51 designates a relatively thin, vertically elongated liquid container which is located between certain horizontal rows of ducts 25 and may be in good thermal contact with the inner row of ducts as shown in Fig. 2 so as to provide not only for quickly cooling liquid within the container, but also to provide a good thermal conductor between the air circulating adjacent the cooling unit and the pipe loops 24 of the unit. A water inlet pipe 52 is connected with the water supply main and with a T 53 connected by pipe 54 with the upper part of the container 51 and by a pipe 55 with the upper part of the container 42. A pipe 56 connects the bottom portions of the containers 51 and 42. A pipe 57 connects the container 42 with a faucet 58.

In operation the cooling unit will chill the air within the chamber 22 and cause it to descend as indicated by arrows 60 and 61 so that it will gravitate into the chamber 21 through the flue 41. On being warmed by contact with the food in the chamber 21, the air will ascend as indicated by arrows 62 to the top of the cabinet and then through the passage 47 to the cooling chamber. Some of the warm air ascending as indicated, will pass in contact with the container 42 and will therefore tend to maintain the temperature of liquid therein at a substantial higher degree than the temperature of the liquid in the container 51. In this way circulation by convection will be maintained between the containers 51 and 42, so that, although no water is drawn from the faucet 58 for a considerable period, the water in the water cooling system will not be frozen.
 30 35 40

The water cooling system may be constructed and arranged so that the temperature of the water drawn from the faucet will remain approximately constantly at the desired temperature for drinking purposes. In warm weather, when the refrigerant machine operates more frequently, the tendency 45 toward reduction of temperature of the container 51 is counteracted by more rapid circulation of the water through the containers due to a higher temperature of the container 42.
 50 55

If desired, the piping could be arranged so that water would flow to the faucet 58 more rapidly from the container 51 than from the container 42, in order that the coldest body 60 of the stored water would be used for drinking purposes.

While the form of embodiment of the present invention as herein disclosed, constitutes a preferred form, it is to be understood that 65 other forms might be adopted, all coming

within the scope of the claims which follow.

What is claimed is as follows:

1. Refrigerating apparatus comprising a cabinet having communicating food and cooling chambers, a cooling unit within the cooling chamber, a horizontal partition separating the chambers and providing a flue for admitting chilled air to the food chamber, a vertically elongated liquid container providing a vertical partition separating the chambers and arranged to permit warmer air to pass above the container from the food chamber to the cooling chamber, a liquid container closely adjacent the cooling unit, and ducts respectively connecting the bottom and top portions of said containers. 70 75 80

2. Refrigerating apparatus comprising a cabinet having communicating food and cooling chambers, a cooling unit within the cooling chamber, said unit including a header and a plurality of horizontal rows of refrigerant ducts depending from the header, a vertically elongated liquid container located between certain rows of ducts, a vertically elongated container spaced from the unit and providing a portion of the partition separating the chambers, and ducts respectively connecting the bottom and top portions of said containers. 85 90

3. Refrigerating apparatus comprising a cabinet having a food chamber and a cooling chamber communicating with the food chamber; a cooling unit in the cooling chamber; and means for containing a liquid and providing for the circulation thereof, said means comprising a container chilled by the cooling unit, a container subjected to warmer air circulating in the food chamber, and ducts connecting the containers to provide for circulation of liquid between the containers and in which the second mentioned container provides a portion of the partition separating the chambers of the cabinet. 95 100 105

4. Refrigerating apparatus comprising a cabinet having a food chamber and a cooling chamber communicating with the food chamber; a cooling unit in the cooling chamber; and means for containing a liquid and providing for the circulation thereof, said means comprising a container chilled by the cooling unit, a container subjected to warmer air circulating in the food chamber, and ducts connecting the containers to provide for circulation of liquid between the containers and in which the liquid containing means comprises a container in close proximity to the cooling unit, a container spaced from the unit and providing a portion of the partition separating the warmer part of the food chamber from the cooling chamber. 110 115 120

5. Refrigerating apparatus comprising a cabinet having a food chamber and a cooling chamber communicating with the food chamber; a cooling unit in the cooling chamber; and means for containing a liquid and 130

providing for the circulation thereof, said means comprising a container chilled by the cooling unit, a container subjected to warmer air circulating in the food chamber, and ducts connecting the containers to provide
5 for circulation of liquid between the containers and in which the first mentioned container is disposed in thermal contact with the cooling unit and in heat absorbing relation to the cooling unit and air circulating
10 past the unit.

In testimony whereof I hereto affix my signature.

RALPH H. CHILTON.
